CLAIM

The ornamental design for a military style shirt, as shown and described.

DESCRIPTION

FIG. 1 is an enlarged front perspective view of a military style shirt showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged front perspective view thereof, as worn;

FIG. 9 is an enlarged partial rear view of the shirt's sleeve; the arm in a straightened position and showing the shirt's reinforced elbow; and,

FIG. 10 is an enlarged partial rear view thereof; the arm in a bent position.

The broken lines, showing portions of the human form, in FIGS. 8-10, form no part of the claimed design. The remaining broken lines on the surface of the shirt represent stitching.
